CLAIM

The ornamental design for a finger ring, as shown and described.

DESCRIPTION

FIG. 1 is a front perspective view of a finger ring showing my new design;

FIG. 2 is a top plan view;

FIG. 3 is a side elevational view;

FIG. 4 is a front elevational view;

FIG. 5 is an elevational view of the side opposite that shown in FIG. 3;

FIG. 6 is a bottom plan view; and,

FIG. 7 is a rear elevational view.

The broken line showing of gems is for illustrative purposes only and forms no part of the claimed design.

FIG. 1
